CLAIM

The ornamental design for a container lid, as shown and described.

DESCRIPTION

FIG. 1 is a top front side perspective view of a container lid showing my new design;

FIG. 2 is a top view of the container lid;

FIG. 3 is a front view of the container lid;

FIG. 4 is a rear view of the container lid;

FIG. 5 is a left side view of the container lid;

FIG. 6 is a right side view of the container lid;

FIG. 7 is a bottom view of the container lid; and,

FIG. 8 is a front view of the container lid in an alternative position.

The broken lines in FIG. 8 are illustrative of environmental structure forming no part of the claimed design.
